(57) **CLAIM**

The ornamental design for an electric connector, as shown and described.

DESCRIPTION

FIG. 1 is front view of an electric connector showing my new design;

FIG. 2 is a left side view thereof;

FIG. 3 is a right side view thereof;

FIG. 4 is a top plan view thereof;

FIG. 5 is a bottom view thereof;

FIG. 6 is a front, left side, bottom perspective view thereof; and,

FIG. 7 is a front, right side, top perspective view thereof. A rear view is omitted because the rear view is symmetrical to the front view.

The broken lines in the drawings are for the purpose of illustrating portions of the article that form no part of the claimed design.
